UNITED STATES PATENT OFFICE.

DUNCAN D. McBEAN, OF NEW YORK, N. Y., ASSIGNOR OF ONE-HALF TO ALBERT H. GRAVES, OF CHICAGO, ILLINOIS.

METHOD AND APPARATUS FOR CONTROLLING HILL AND EMBANKMENT SLIDES.

1,323,884.

Specification of Letters Patent.

Patented Dec. 2, 1919.

Application filed December 20, 1915. Serial No. 67,757.

To all whom it may concern:

Be it known that I, DUNCAN D. McBEAN, a citizen of the United States, residing at New York, in the borough of Manhattan and State of New York, have invented certain new and useful Improvements in Methods and Apparatus for Controlling Hill and Embankment Slides, of which the following is a specification.

10 This invention relates to improvements in method and apparatus for controlling hill and embankment slides, and refers more specifically to means for arresting and preventing the encroachment of unstable hills 15 or embankments of earth, rock and the like, upon passageways or other areas menaced by such slides.

It is a matter of common knowledge that canals, railways, roadways and other areas 20 are often menaced by unstable earth or rock adjacent thereto. For illustration, in excavating for a canal or railway it is often necessary to make deep cuts, and very often these cuts extend through valleys or depressions between much higher hills or elevations. Particularly in the case of canal 25 construction, the water which is admitted to the canalway, after the latter has been excavated, softens the underlying and adjacent strata so that expensive and sometimes 30 disastrous slides occur. The slides which have occurred, and are now occurring, on the Panama Canal are notable examples of the conditions for which my present invention affords a remedy.

It is the object of the present invention to provide a simple method, and means for carrying the method into effect, for eliminating such hazards from slides.

35 First describing generally the method of my invention, I first sink one or more buttressing structures within, or partly within, the area to be protected from encroachment, *i. e.*, at, or substantially at, the toe of the slide.

40 The buttressing structure or structures are of sufficient dimensions, particularly as to depth, and length in the direction parallel to the advancing movement of the slide, and of such weight that when installed it or 45 they will immovably withstand encroaching movement of the slide both as regards the advancing movement of the slide and as regards any tendency of the slide to underflow and lift up the buttressing structure or

structures. Where the extent of the slide is 55 considerable I prefer, as a matter of economy in cost, to sink a plurality of the buttressing structures extending transversely of the way, *i. e.*, in alinement with the direction of descent of the slide, at spaced apart 60 intervals, and to then sink a retaining structure arranged to extend along those ends of the buttresses toward or projecting into the slide; this retaining structure or structures being supported by the ends of the buttressing structures. Of course, if the extent of the slide is small considered in the direction of the length of the way to be protected, the buttressing structure may itself be a sufficient slide retaining structure, but ordinarily 70 the retaining structure proper will be required, arranged as above described.

Having thus installed the retaining structure or structures, I next proceed to construct the way across the protected area. If 75 a retaining structure has been combined with the buttressing structures the way will, of course, be constructed in the lee of the retaining structure and above the buttressing structures. In practice, caisson structures will usually be utilized as the buttressing and retaining wall structures, and ordinarily the buttressing caissons will have to be built to extend more or less above the surface level of the way, as, for example, 80 more or less above the bottom level of the canal. Accordingly the construction of the way will involve removing certain portions of the upper parts of the buttressing caissons or structures down to or slightly below 85 the level of the way and thereafter constructing the way proper across or along the protected area.

With the foregoing outline of the general method, the following description of a preferred method and means for carrying the invention into effect will be readily understood.

In the accompanying drawings—

Figure 1 is a transverse vertical sectional 100 view showing a hypothetical slide condition, and in dotted lines the cross-sectional outline of a canal which has been filled by the slide;

Fig. 2 is a view similar to Fig. 1 on a 105 much smaller scale but showing caissons installed to control the slide and the canal-way formed above the buttressing caissons;

Fig. 3 is a transverse vertical sectional view through a buttressing caisson and the adjoining retaining caisson; this view showing the condition after the caissons have been installed but before the canalway has been constructed, the outline of the latter being indicated in dotted lines.

Fig. 4 is a plan view showing the manner in which the retaining caissons extend along the ends of the buttressing caissons;

Fig. 5 is a detail of a corner portion of one of the caissons showing a simple and preferred manner of building the latter;

Fig. 6 is a detail of one of the anti-friction devices between adjoining caissons.

Assuming the invention is to be applied to protect a canalway, and that the slide has encroached or flowed down upon the way, under ordinary conditions the encroaching material will have to come to rest either because of its surface having assumed its angle of repose or because the most advanced part of the slide has been underflowed by the weight of the material behind it, and thus elevated the encroaching parts until the weight of the accumulated upheaved portions counterbalances the pressure tending to advance the slide still farther, so that the slide as a whole has come to rest.

However, whether the slide has completely come to rest or not, I first erect or place the buttressing caisson or caissons in position to extend across the canalway, or partly across the canalway, *i. e.*, in those positions in which they are to be sunk vertically into place. These buttressing caissons, designated as a whole *a* in the drawings, may be constructed in any usual or preferred manner which enables them to be sunk by progressively increasing their weight while excavating beneath them in a working chamber. The caisson construction shown comprises vertical side walls of sheeting *b* externally smooth, or substantially smooth, and internally reinforced and supported by suitable timbering, as for example by the horizontally disposed courses of walling *c*. The walls are so constructed that they may be increased in height from time to time as the lowering of the caisson and the filling of its interior with masonry proceeds. Desirably, and as shown, the further reinforcements of the walls are provided by a series of vertically disposed rods *d* having their lower ends attached to the floor *e* of the caisson and extending upwardly through the several courses of walling, as shown clearly in Fig. 5.

The floor of the caisson is made amply strong to withstand the full weight of the masonry when the box part of the caisson is filled with masonry to the maximum height which the caisson is to be built. Moreover, the floor is made air-tight, or

substantially air-tight, inasmuch as it serves as the roof of the pneumatic working chamber.

To form said pneumatic working chamber the side walls of the caisson are extended downwardly, say some six or seven feet, *i. e.*, far enough to enable workmen to work therein beneath the floor of the caisson, and, as usual, the lower margins of these side walls, designated *a'* in the drawings, are made comparatively sharp so as to readily penetrate the earth. These side walls are also made air-tight, or substantially so. Where the caisson is comparatively large in area, the working chamber is desirably divided into a plurality of compartments by transverse partitions *f* and *g*; these partitions serving to brace the side walls and to support the overlying floor of the caisson.

Suitable shafts are constructed to afford access of the workmen to and from the working chamber, and to enable the air under pressure to be introduced and the excavated material to be removed. In the buttressing caisson now being described, a plurality of these shafts *h* are provided, spaced at intervals apart throughout the length of the caisson.

Each caisson is provided with a suitable air-lock *i* of any usual or preferred construction and serving the usual functions. As will be well understood by those skilled in the art and familiar with caisson practice, masonry or other heavy material is filled in to the caisson box so as to progressively increase the weight of the caisson structure as a whole as the excavation underneath it proceeds; the caisson being thus gradually forced downwardly as fast as the excavation proceeds, and the added weight in the caisson serving to overcome the increasing frictional resistance on the sides of the caisson. I prefer to use concrete *k* for filling in the caisson progressively around the shafts, inasmuch as this material can be put in in semi-liquid or plastic state and is comparatively heavy. However, the caisson structure will ordinarily have to be built and carried up to a height above the bottom level of the canalway or roadway in order that it shall have sufficient weight to overcome the resistance to its descent. Accordingly, and as a matter of economy of construction, I prefer to fill in that part of the caisson which will be above the bottom level of the canalway or roadway in the final position of the caisson, with weighting material which may be readily removed. Preferably I employ broken stone or broken concrete *j*, which may be either piled in heterogeneous or may be laid in courses so as to form true masonry construction. Concrete might, however, be deposited throughout the full depth of the caisson box, and those portions thereof which extended above the de-

sired final level of the way be blasted out or otherwise removed.

Having constructed and sunk in place the buttressing caisson, or a series of buttressing caissons, spaced apart at suitable intervals, I next proceed to place the retaining caissons, designated in the drawings as a whole *l*, in such position that they extend along the ends of the buttressing caissons and between the latter and the slide. That is to say, the retaining caissons are sunk adjacent to the ends of the buttressing caissons so as to overlap and be supported by the ends of the latter and so as to form in effect retaining walls which receive the direct lateral thrust of the slide. The retaining caissons *l* are preferably constructed substantially like the hereinbefore described caissons *a*, except that they will ordinarily be carried up somewhat higher than the buttressing caissons, preferably at least as high as the depth of the canal, and they may be filled in with solid concrete to their full height. Parts of the retaining caissons corresponding to those of the buttressing caissons are correspondingly lettered.

Inasmuch as the retaining caissons may be forced into bearing with the buttressing caissons while the former are being sunk, I prefer to provide anti-friction devices between the adjoining parts of the caissons. These anti-friction devices may be rollers, as indicated at *m*, or some simpler device, for lessening the friction, as for example steel plates.

It will, of course, be understood that inasmuch as the buttressing and retaining caissons are sunk independently of each other, it by no means follows that they must both be sunk to the same depth. The end of the buttressing caisson should afford such extent of bearing and support for the side of the retaining caisson that there will be no tendency of the latter to tilt over under the weight of the slide. The length, depth and weight of the buttressing caisson should be such as to make of it an immovable, or substantially immovable, buttress, and this stability will be enhanced, of course, when the retaining caisson is installed. It will be obvious that the length and depth, and therefore the weight, of the buttressing caissons will be such as to suit the conditions of the particular problem in hand. If the sub-strata are soft and yielding to a depth below that reached by the bottom of the buttressing caisson, the latter will be sunk deep enough so that the superposed load of masonry renders it secure against the underflowing lifting tendency of the slide. On the other hand, if solid foundation be reached, the caisson need only be sunk far enough into such foundation to anchor it firmly against lateral movement. There will

in such case be no substantial tendency of the slide to lift the caisson, and the latter need therefore only extend down to the firm stratum. In case the canal or other way be formed between two slides, both of which must be guarded against, it is of course obvious that retaining caissons will be sunk at both ends of the buttressing caissons, and in that case the combined caisson structure, *i. e.*, the retaining caissons at each side and the buttressing caisson between, will form in effect arches between the two slides.

The construction of the canal, roadway or other surface above the buttressing caissons, after the structure as a whole has been placed, requires no special description. It will be observed that the length of the transversely disposed buttressing caissons is a little greater than the bottom width of the canal, so that the end walls of these buttressing caissons may be left intact when the canalway is built. After the retaining caissons have been placed it will ordinarily be desirable to cover them with earth extending from the canal side of the caisson upwardly and backwardly at a safe angle of repose. By thus covering them any tendency to tilt over toward the canal will be minimized.

It will be obvious that the details of construction and arrangement may be considerably varied without departing from the invention, and the appended claims are to be construed as broadly as is commensurate with their terms and the state of the art.

I claim as my invention:

1. The method of making and protecting a passageway through a section of land that is liable to produce slides, which consists of progressively sinking a plurality of buttressing caisson structures in such a manner that they will lie in spaced apart relationship and individually extend entirely across the proposed passageway; of sinking one or more retaining caissons parallel with the sides of said passageway and so positioned as to lie between the slide developing earth and the ends of the buttressing caisson structure and project above the height of the latter; and finally of grading down the upper portion of the buttressing caisson structures as far as the lower level of the said passageway.

2. The method of protecting a passageway menaced by a slide, which consists in sinking an abutment caisson to extend beneath and transversely of said passageway, and then sinking a retaining structure to extend along the way, between the encroaching part of the slide and said abutment caissons and supported by the latter.

3. The method of protecting a passageway menaced by a slide, which consists in sinking an abutment caisson to extend beneath and transversely of said passageway,

and installing a retaining structure to extend along the way, between the encroaching part of the slide and said abutment caisson and supported by the latter.

5. 4. The method of protecting a passageway menaced by an earth slide, which consists in sinking, in spaced apart relation, a plurality of buttressing caissons, arranged to underlie and extend transversely of, said way, weighting said caissons so that they will immovably withstand lifting under the underflowing action of the slide, and installing a retaining structure alongside of said way, between the encroaching part of 10 the slide and the ends of the abutment caissons and supported by the latter.

5. The method of protecting a passageway menaced by an earth slide, which consists in sinking, in spaced apart relation, a plurality of buttressing caissons, arranged to underlie, and extend transversely of, said way, weighting said caissons so that they will immovably withstand lifting under the underflowing action of the slide, and sinking 20 a retaining caisson or caissons alongside of said way, between the encroaching part of the slide and the ends of the abutment caissons.

6. The method of making and protecting 30 a passageway along a course menaced by a slide, which consists in sinking one or more abutment caissons arranged to extend transversely of the proposed passageway, sinking one or more retaining caissons to extend 35 along the way, between the encroaching part of the slide and said abutment caisson or caissons and finally removing the upper portions of the buttressing caissons down to the level of the bottom of the proposed way 40 and constructing the latter above said buttressing caissons.

7. In a slide retaining construction, the combination of a caisson embedded in front of and obstructing the slide, and a buttressing 45 caisson, extending laterally from the

obstructing caisson, suitably embedded and weighted with a heavy filler and butted against the side wall of the obstructing caisson to hold the latter against lateral displacement due to the pressure of the slide. 50

8. In a slide retaining construction, the combination of a plurality of caissons embedded end to end along the front of and obstructing the slide, and a plurality of buttressing caissons spaced apart and extending 55 laterally from the obstructing caissons, said buttressing caissons being suitably embedded and weighted with a heavy filler and butted against the side walls of the obstructing caissons to hold the latter against 60 lateral displacement due to the pressure of the slide.

9. The method of protecting a proposed passageway from the encroachment of embankment slides which consists in building 65 one or more buttressing structures at right angles to the proposed passageway, said structures being of greater width than said proposed passageway and terminating at the upper level thereof, and in removing 70 the upper portions of the structure and in constructing the passageway in the opening produced by such removal.

10. The method of protecting a proposed roadway from embankment slides which 75 consists in building and sinking a plurality of spaced apart parallel buttressing structures greater in width than the proposed roadway and at right angles thereto, said structures to be sunk to such depth that the 80 upper portions thereof are at a level with the top of the proposed roadway; in removing the upper portions of said structures to a depth and width of the proposed roadway; and in finally building the roadway 85 in the channel so produced.
